UNITED STATES PATENT OFFICE

JAMES W. JOHNSTON, OF MANCHESTER, NEW HAMPSHIRE, ASSIGNOR TO LACENE MANUFACTURING COMPANY, OF MANCHESTER, NEW HAMPSHIRE, A CORPORATION OF MAINE

GRADING MACHINE

Application filed February 4, 1929. Serial No. 337,245.

This invention relates to grading machines of the kind which grade die-cut pieces of leather such as cut soles, taps, heel-lifts, counters and other blanks in accordance with the thickness of the thinnest spot as determined by the detector. The invention consists in certain improvements upon the well-known grading machines covered by a number of patents to Elmer P. Nichols and by the 10 patents and pending applications of Leander A. Cogswell. These improvements relate particularly to the mechanism for guiding the blank as it is fed to the machine, the mechanism for feeding and propelling the 15 blanks through the machine and the mechanism for controlling the starting of the preservation of measurements as determined by the detecting mechanism for transmission to the grading mechanism.

20 While the invention is of more general application, it is particularly designed for application to a grading machine of the general type illustrated in the Nichols Patent No. 1,130,321, dated March 2, 1915, and by way of 25 illustration, but not of limitation, I shall therefore describe the invention in connection with and as embodied in a machine of that type.

In the accompanying drawings:

30 Fig. 1 is a plan view, partly in section, of a grading machine embodying the present improvements;

Fig. 2 is a side elevation of that part of the machine which is at the rear of a vertical 35 transverse plane indicated by line $x-x$;

Fig. 3 is a side elevation of that part of the machine which is forward of the line $x-x$;

40 Fig. 4 is a central, vertical, longitudinal section of the machine shown in Figs. 1, 2 and 3;

Fig. 5 is a plan view on an enlarged scale, partly in section, of the front end of the machine;

45 Fig. 6 is a side elevation on an enlarged scale, partly in section and partly broken away, of new tripping mechanism and other parts of the mechanism shown in Fig. 5;

50 Fig. 7 is a detail in section on line 7-7 of Fig. 6; and

Fig. 8 is a detail of the latch, hereinafter described, associated with the new mechanism for guiding the blanks into the machine.

As the illustrated machine as a whole is substantially similar in purpose, construction 55 and operation to said well-known Nichols and Cogswell grading machines, particularly that shown in said Nichols Patent 1,130,321, it will not be necessary to describe it in all of its details but only to give such general description 60 as will serve to make clear the improvements which constitute the subject matter of this invention.

Leather blanks such as soles, taps, heel-lifts, counters, etc. used in the manufacture 65 of shoes, are customarily graded in accordance with the thickness in "irons" of the thinnest spot of the blank or of some selected portion of the blank. Grading machines of the kind to which the present invention relates are constructed and arranged to measure and determine the grade of successive blanks of stock fed through the machine by a feeling or detecting operation and then to grade the several blanks in accordance 75 with the thickness of the thinnest spot so determined by the detaching mechanism. There are various kinds of grading operations performed by various species of grading mechanism. The term grading mechanism is a generic term, established in this art, and includes devices for stamping or marking each blank with its grade number, evening or skiving the blank as a whole down to the grade or thickness of its thinnest spot, indicating on a visual indicator the grades of 80 the several blanks and sorting or distributing the blanks in accordance with their grades.

Two or more species of grading mechanism may be and usually are contained in one machine and in the Nichols machine selected for illustration there are included mechanism for skiving or evening the blanks and mechanism for stamping or marking the blanks in accordance with their grades. It will be understood, however, that the present improvements are not restricted to any specific kind of grading mechanism since they are chiefly concerned not with the mechanisms for ultimately grading the blanks but with devices 85 90 95 100

associated with the detecting means for guiding the blanks to the detecting means, feeding the blanks away from the detecting means and thence through the machine toward the 5 grading mechanism, and starting the transmission to the grading mechanism of the measurements determined by the detecting means.

Referring to the drawings 10 is the main 10 frame of the machine and 11 is a continuously rotating main driving shaft journaled in bearings in the machine frame. At one side of the frame the shaft 11 is provided with the usual driving pulley and clutch mechanism and at the other side of the frame the shaft 11 carries a pinion 12, which operates through an intermediate gear 13 to drive gear 14 fast on shaft 15 of the upper feeding and detecting roll 16. The shaft 15 is journaled in boxes 19 adjustably mounted in vertical ways 20 on the frame in the usual manner. The lower detecting and feeding roll 17 cooperates with the upper roll 16 to feed and measure the blanks and is carried by a 25 shaft 18 journaled in two boxes 19^a mounted to slide vertically in ways 20. The rolls 16 and 17 are geared together as usual. Directly below roll 17 a cross bar 21 is fixed at its ends to the under sides of boxes 19^a. The 30 cross bar 21, and consequently the roll 17, is normally pressed upward in the usual manner by a pair of bell-crank levers 22, whose depending arms are connected by a spring 22^a. The up and down measuring movements 35 of the detecting and feeding roll 17 are transmitted to the detecting mechanisms at the other end of the machine through setting mechanism, which includes the usual lever 23 pivoted to the machine frame at 24 below 40 the cross bar 21, having at its free end a gear segment which meshes with gear segment 25 fast on rock shaft 26. The rock shaft 26 constitutes the setting shaft from which the measurements determined by the 45 detecting roll are transmitted to the adjustable grading mechanism in the usual way as more fully explained in said Nichols patent. The cross bar 21 is connected to lever 23 by two vertical posts 28, fixed as usual to 50 cross bar 21 and extending loosely through holes in lever 23. Stop nuts 27 are screwed on to the posts 28 below the lever and spring 27^a between the lever 23 and the cross bar 21 yieldingly holds the lever against stop 55 nuts 27. The foregoing parts, and other associated details not herein shown, are substantially as shown in said Nichols Patent 1,130,321, to which reference is made for fuller description.

60 The lower detecting roll 17 is made in two sections, as shown in Fig. 5, separated at the middle to provide an annular groove through which runs the upper stretch of a flexible, endless, feeding belt 29 mounted 65 upon and driven by a driven pulley 30 at

one end and an idle pulley 31 at the other end. Pulley 30 is fixed to a transverse shaft 32, journaled in bearings provided in the frame of the machine, and is rotated by a sprocket wheel 33 fixed to the shaft and driven through chain 34 by sprocket wheel 35 fast on a stub shaft 36, journaled in a bearing block 37. The stub shaft 36 also carries a gear 38 which is continuously driven by pinion 12 on main driving shaft 11. Through 70 the connections described the detecting and feeding roll 17 and the endless belt 29 are driven by the main shaft 11 at the same surface speed and in the same direction as indicated by arrows in Fig. 4. The idle pulley 75 31 is journaled on a bracket 39 held in position on the frame of the machine by two screws 40 extending through slots in the bed plate. Bracket 39 may be adjusted forward and back by means of a threaded stem 41 screwed into a threaded socket on bracket 39 and extending forwardly therefrom to the front of the machine where it is provided with a head 42, which serves as an abutment for one end of a coil spring 43, surrounding 80 the stem 41 and bearing at its opposite end against an abutment lug 44 on a bracket or shelf 83 attached to the machine frame 10. The spring 43 serves at all times to hold the endless belt 29 taut.

Heretofore grading machines of this kind have been equipped with an endless chain for feeding and propelling the blanks from the detecting rolls to the grading mechanism. Such chains have been mounted on sprockets located in the space between the detecting rolls and the grading mechanism so that it was not until the blank had passed through the detecting rolls and far enough beyond to engage the sprocket chains that the chain took up and carried on a forward feeding of the blank through the machine. In the present construction it will be observed that the feeding belt 29 passes over a pulley 31 in front of the detecting rolls and consequently the belt extends forward of the detecting rolls with the result that the operative reach of the feeding belt is available for the entire distance forward to and even beyond the detecting rolls.

Moreover, as sprocket chain afford substantially no frictional engagement with the leather blanks it has been necessary and has been the practice to provide the chains with spurs or prongs to penetrate the surface of the blanks sufficiently to prevent slipping and to propel the blanks through the machine. Excepting for a certain amount of disfigurement of the blanks the use of spurs on the feeding chains was not particularly objectionable when operating upon relatively thick, stiff material such as outer soles. When operating, however, upon relatively light, thin and flexible blanks the use of prongs, spikes or spurs on the feeding chain 120 125 130

is objectionable for a number of reasons. The perforation and disfigurement of a thin blank by the spurs is much more serious than in a thick heavy blank. As the spurs are necessarily placed some distance apart on the chain links they engage the blank only at more or less widely separated points, sometimes at only one or two points, with the result that the blank may swing sideways out of its proper alignment; and, most objectionable of all, the engagement of a thin flexible blank by the spurs only at isolated and separated points sometimes causes it to buckle or crumple instead of being fed flat and smooth through the machine. With the present feeding mechanism the conveyor is in the form of an endless belt 29 made of leather or other suitable fabric with a friction-gripping, working surface which engages and frictionally grips the blank throughout its entire length and so holds the same against buckling or being otherwise displaced and at the same time avoids any perforation or disfigurement of the blank whatever. The blank is supported on its upper side and held down against the belt by a presser shoe 47, hereinafter described. The mechanism will handle thick and heavy blanks equally well.

30 The frame of the machine includes a bed plate 44 formed upon its top side with a groove 45 through which the upper stretch of the belt 29 passes and by which this stretch of the belt is supported. In front of the feeding and detecting rolls is another bed plate 46 to the under side of which the bracket 39 is secured.

35 Directly above the top stretch of the belt 29 and parallel thereto is a long presser shoe 47, to the ends of which are pivoted two vertical stems or posts 48 and 49, the upper ends of which pass loosely through holes provided in brackets 50 and 51 mounted on the machine frame. Stop nuts 52 are screwed on the posts 48 and 49 above the supporting brackets to limit downward movements of the posts and shoe 47. Between each of the brackets 50, 51 and the shoe 47 are coil springs 53 which yieldingly urge the shoe 47 downward toward belt 29. The under side of shoe 47 is smoothly polished to afford an anti-friction, sliding surface for the blanks being fed through the machine, so as to offer the least possible friction resistance.

40 When a sole or other blank is to be passed through the machine it is fed in either by hand or by feeding mechanism upon the bed plate 46 and beneath the usual gate 54 until it is engaged by the nip of the feeding and detecting rolls 16 and 17. As soon as the blank is gripped by these two rolls it is propelled forward thereby into position between the presser shoe 47 and the traveling belt 29 so that thereafter until the rear or following end of the blank leaves the rolls

45 16 and 17 the blank is moved forward by the joint action of the rolls and the belt. After the rear or following end of the blank leaves rolls 16 and 17 the belt 29 by frictional engagement with the blank continues to propel it forward toward and past the grading mechanism at the delivery end of the machine. When the leading end of the blank emerges from beneath the shoe 47 it passes into position on top of an anvil 55 and at the same time depresses a pair of trip arms 56 which, as usual, operate a grade marking mechanism to cause a downward stroke of the type wheel 57 upon the top side of the blank. The type wheel 57 as usual has on its periphery a series of dies or types corresponding to the several grade measurements. This type wheel, it will be understood, has been previously automatically adjusted to correspond to the grade measurement as determined by the detecting rolls, by the usual well-known mechanism employed in grade marking machines of this type, and more fully described in said Nichols patents to which reference may be had for further details. Parts only of the mechanism are illustrated herein, including the double ratchet wheel 58 fixed on shaft 26. Pawls 59 and 60 cooperate with the opposed ratchet sectors of wheel 58, the teeth of one ratchet facing in one direction and the teeth of the other ratchet facing in the other direction. These two pawls function as usual. The pawl 60 is connected as usual by link 61 with the gate 54 at the front or entrance end of the machine. So long as the gate is held elevated either by the blank or by mechanism in the machine, the pawl 60 is held retracted and inactive. The pawl 59 is moved by gravity into engagement with its ratchet on wheel 58 and is made with a tail piece 63 normally held depressed, with the pawl inactive, by a vertically movable gravity plunger 64. As usual in grading machines of this type, and as will be understood by reference to said Nichols Patent No. 1,130,321, when the pawl 59 is in engagement with its ratchet the wheel 58 and its rock shaft 26 will be free to turn in response to successive thinner spots as determined by the detecting mechanism, but not in the opposite direction, thus preserving the thinnest measurement of the blank for transmission to the grading mechanism. When both pawls 59 and 60 are in engagement with their respective ratchets the shaft 26 will be locked against movement in either direction.

50 Heretofore the gravity plunger 64 has been lifted to set pawl 59 by the lifting of trip arm 70 (hereinafter described) when the forward or leading end of the blank reaches and lifts the trip member carried by said trip arm 70. It is one of the features of my present invention to operate the gravity plunger 64 independently of the

trip arm 70 by means of a lever 65 fulcrumed at 66 on a bracket supported by the frame of the machine. One end of the lever 65 is pivoted at one end to the gravity plunger 64 and the other end, extending in the opposite direction from the fulcrum, is cooperatively disposed with relation to a cam 67 fast on one end of a short horizontal spindle 68 journaled in bearings on bracket 51 close to the upper roll 16. The spindle 68 extends inwardly to a point over the path of the blanks and has fixed to it at that point a pair of depending trip fingers 69, occupying positions at opposite sides of the forward end of the shoe 47 and closely adjacent thereto. The fingers 69 extend inward close to the nip of the rolls 16, 17, so that as the blank emerges from between the rolls it immediately engages the trips 69 swinging them away from the rolls and thereby turning shaft 68 and cam 67. The cam 67 swings lever 65 on its fulcrum thereby lifting the gravity plunger 64 and permitting pawl 59 to engage its ratchet, thus rendering the setting mechanism operative to preserve the measurement of the thinnest spot as determined by the detective rolls. Pawl 59 remains in engagement with its ratchet until the rear or following end of the blank passes the trip fingers 69, whereupon the gravity plunger 64 falls to its normal position where it rests on top of the frame 10 with the pawl 59 out of action and the trip fingers 69 restored to their normal position shown in the drawings; but meanwhile the blank will have left rolls 16, 17 and the pawl 60 will have been locked to prevent ratchet wheel 58 and setting shaft 26 from moving in the direction to record further upward motions of roll 17. The return movement of the trip fingers 69 is brought about by the fall of the gravity plunger 64 acting through lever 65 to restore the cam 67 and shaft 68 to the position shown in the drawings without the assistance of a spring. This automatic restoration is made possible by the fact that the cam 67 is rotated by the blank less than 90° and functions as a crank arm when the blank moves out of engagement with the trip fingers 69.

Among the advantages of this new tripping mechanism for setting pawl 59 and starting the transmission of the thinness measurements to the grading mechanism, is the fact that the action of the trip fingers 69, 69 is exceedingly light and sensitive as compared to the action of the weighted rod 70 heretofore employed, and that the trip may be actuated immediately upon the emergence of the advance end of the blank from rolls 16 and 17 and the measuring action therefore may be started sooner. The very light action of the trip 69 is of great importance in operating upon thin, light blanks, which would be likely to curl or crumple, and so

both damage the blanks and clog the machine, if the trip should offer serious resistance to their passage. The non-curling effect of the light acting trip is assisted by the fact that the trip fingers 69, 69 extend closely alongside the presser shoe 47, which extends well forward toward the trip of the rolls with its tip received in grooves in the upper roll 16, so that the presser shoe promptly comes into action to help hold the blanks flat and smooth while the trip fingers 69 are being actuated.

The effective measuring or detecting of a blank by the detecting rolls starts when the advance or leading end of the blank emerges from the detecting rolls and operates the trip fingers 69 to set the thinness measuring pawl 59, and stops when the gate 54 falls to the table after the passage of the rear or following end of the blank, thereby setting pawl 60 into engagement with its ratchet. At this stage therefore the ratchet wheel 58 and its shaft 26, from which the detected measurements are transmitted to a grading mechanism, are locked against further movement in either direction. When the following end of the blank passes out from under the trip fingers 69 the gravity plunger 64 will be free to drop as already explained, thereby unlocking pawl 59 but leaving pawl 60 still locked until the gate 54 is again lifted.

The mechanism for operating the gate is controlled by the passing blanks, and consists of the trip arm 70, fixed at one end to a rock shaft 71 and thence extending toward the rear of the machine over the path of the blanks. Near its free end the arm 70 carries an adjustable weight 77, provided with a set screw, and a depending bracket 78, also provided with a set screw. The bracket 78 is made at its lower end with a bearing in which is journaled an axle 79 carrying two trip wheels 80 and 81, one at each side of the bracket. Wheels 80 and 81 normally rest in the groove 45 of the bed plate, one at each side of the presser shoe 47, directly in the path of the blanks. The gate 54 is normally held in open or elevated position (with pawl 60 disengaged) by the weight of arm 70, and the parts carrier by it, acting through rock shaft 71, the short arm 72 fixed to rock shaft 71, and the lever 73. The lever 73 is fulcrumed at 74 on the bracket 51. One end of lever 73 engages underneath arm 72, and the other end is connected to gate 54 by a link 75, which has a pin and slot connection at its upper end and a pivot pin 76 connecting its lower end to the gate. This gate opening construction is substantially as shown in the Cogswell Patent No. 1,366,889, dated January 25, 1921.

The trip bracket 78 may be adjusted on rod 70 according to the length of the blanks being operated upon and the desired timing of the operation of the gate. Preferably it is so ad-

- justed that the advance or leading end of the blank engages the trip rolls 80 and 81 just as the following end of the blank approaches the rolls 16 and 17, thus lifting the rod 70 and lowering the gate before the blank passes out from between rolls 16 and 17. If the blank has already passed from under the gate the gate will drop to the table and set pawl 60 into locking position; if the blank is still under the gate when rod 70 is lifted the gate will fall until its foot 62 rests on top of the blank, where it may be arrested by reason of the slot and pin connection of link 75, in which case pawl 60 will still be held disengaged, but as soon as the blank passes out from under foot 62 the gate will fall to the table and lock pawl 60. When thus locked, the pawl 60 will remain locked so long as the blank supports the trip wheels 80 and 81. This enables the blank to reach and be operated on by the grading mechanism, for example the stamping wheel 57, while the grade setting mechanism, including the wheel 58 and setting shaft 26, remain locked by pawl 60 in accordance with the measurement as determined by the detecting rolls. When the following end of the blank passes out from under the trip wheels 80, 81, the weight of the parts carried by rod 70 will swing the latter downward, thereby lifting the gate 54 and unlocking pawl 60 and so restoring the machine to position for receiving another blank. The unlocking of pawl 60 will permit the detecting roll 17 to be lifted to the limit of its upward movement by spring 22. Thus it will be seen that the automatic opening of the gate, controlled by the blank through wheels 80 and 81, and the unlocking of ratchet wheel 58 and setting shaft 26, may be delayed and timed to occur after the following end of the blank has passed the detecting rolls 16 and 17, and after the leading end of blank has been acted upon by the type wheel 57 or by other grading devices if others are used. Also the closing of the gate by the advance end of the blank may be accomplished independently of the setting of pawl 59 and may be delayed until the blank has nearly passed through rolls 16 and 17. The graded blank is discharged from the machine down an incline 82 at the rear end of the machine. As already indicated, other usual instruments may be used at the delivery end of the machine, such as skiving and evening devices or other grading mechanisms, ejecting rolls, etc., as already known in the art.
- Many blanks used in shoe making and required to be graded by machines of this kind are crooked or asymmetrical. For example, the median lines drawn from the end of the heel of a cut sole to the shank and from the shank through the ball to the tip of the toe form a pronounced angle with each other. The part of a cut sole which it is important to grade with accuracy is the forepart and it is therefore desirable that the sole should pass through the machine with the median line of the forepart parallel and substantially coincident with the median line of the machine, that is, approximately midway between the two sections of the detecting roll 17. This is desirable for the further reason that the area of the forepart of a sole which is most important to grade with accuracy is the margin and it is therefore important that one section of the two-part roll 17 should traverse one side of the ball of the sole and the other section the opposite side. For accomplishing this result I have devised an improved guiding and centering device located at the entrance of the machine for guiding and positioning the sole properly as it is sent to the rolls 16 and 17. This mechanism includes the bracket or table 83, fixed rigidly to the frame of the machine, whose top surface in effect constitutes an extension of bed plate 46. The table 83 is formed with a transverse slot 84 within which is a transverse shaft 85, one end of which is formed with right hand threads and the other end with left hand threads. The shaft 85 extends loosely through bearings 86 provided on table 83 at the ends of slot 84. The threaded portions of the shaft extend through threaded lugs 87 formed on the under side of two slides 88 supported on table 83, one at each side of the machine. These slides are guided by the slot 84. Each slide 88 carries at its inner edge an upstanding guide wall or plate 89. The two plates 89, 89 form between them a guide channel or trough for the incoming blank, at all times parallel to the median line of the machine. The shaft 85 is provided with a hand wheel 90 at one end by means of which the shaft may be rotated to shift the slides 88 and the guide plates 89 simultaneously toward and from each other to conform to the width of the blanks being graded. Each guide plate 89 has hinged or pivoted to its inner end an angularly adjustable guide plate section 91 made at its top with an upstanding lug 92. The two lugs 92 are held against the outer sides of two abutment arms 93, each of which is part of a bell crank lever 94 mounted upon and threaded to a shaft 95 journaled in bearings on the frame of the machine. The other arm 96 of each bell crank member 94 engages and slides upon the frame of the machine and serves to hold the member 94 from rotating when the shaft 95 is rotated. About half the length of the shaft 95 is formed with a right hand screw thread engaged with one member 94 and the other half is formed with a left hand screw thread engaged with the other member 94. Thus, when shaft 95 is rotated the two members 94 are simultaneously adjusted toward or from each other. This lateral adjustment of the members 94

is accomplished simultaneously and in like degree with the lateral adjustment of the guide plates 89 by connecting the shafts 95 and 85 to rotate together. Fixed to one end 5 of shaft 85 is a sprocket wheel 97 connected by a sprocket chain 98 with a sprocket wheel 99 fixed to one end of shaft 95, said two sprocket wheels being of the same diameter. Accordingly, when shaft 85 is rotated by 10 means of the hand wheel 90 to adjust guides 89 toward and from each other, shaft 95 will be similarly rotated to adjust members 94 toward and from each other in like manner and to the same extent.

15 In order to adjust and adapt the guides 89 and 91 to either right hand or left hand soles or other crooked blanks the shaft 85 is made bodily shiftable endwise in both directions with respect to the table 83, the collars 100 and 101 serving to limit the extent 20 of such shifting movement. When the shaft 85 is in the position shown in solid lines in Fig. 5 the main guide members 89, 89, will be offset slightly to the right while the angular guide members 91, 91 will be inclined to the left since their lugs 92 will be held in engagement with and fulcrumed on the outer sides of the stationary abutments 93 by means 25 of a tension spring 102. When the shaft 84 is shifted to the left with the collar 101 against the right hand bearing 86 the guides will be moved to dotted line position, the main guide sections 89, 89 remaining in parallelism but offset slightly to the left and 30 the angular guide sections 91, 91 likewise remaining in parallelism but swung to the right, all as shown in dotted lines. In order to hold shaft 85 in either of its shifted positions a latch 103 (Figs. 5 and 8) is provided 35 on the end of table 83 to engage one side or the other of collar 101.

I claim:

1. A grading machine of the kind having 40 detecting mechanism for measuring successive blanks according to thickness, a normally open gate in advance of the detecting mechanism, grading mechanism, setting mechanism responsive to the detecting mechanism and controlling the grading mechanism and 45 normally inoperative to preserve the grade measurements determined by the detecting mechanism, and a trip in the path of the blanks for controlling the gate, said trip being independent of and in advance of the grading mechanism, including in combination a second trip in the path of the blanks 50 adapted to be operated by the blanks independently of the first named trip to render the setting mechanism operative to preserve 55 said grade measurements.

2. A grading machine of the kind having 60 detecting mechanism for measuring successive blanks according to thickness, a normally open gate in advance of the detecting mechanism, grading mechanism, setting 65 mechanism,

mechanism responsive to the detecting mechanism and controlling the grading mechanism and normally inoperative to preserve the grade measurements determined by the detecting mechanism, and a trip in the path 70 of the blanks for controlling the gate, including in combination a second trip in the path of the blanks in advance of the first named trip adapted to be operated by the blanks independently of the first named trip to render the setting mechanism operative to preserve said grade measurements before the first named trip is actuated to close the gate.

3. A grading machine of the kind having 80 detecting mechanism for measuring successive blanks according to thickness, grading mechanism, setting mechanism responsive to the detecting mechanism and controlling the grading mechanism, a normally open gate in 85 advance of the detecting mechanism, a trip in the path of the blanks for controlling the gate, said trip being independent of and in advance of the grading mechanism, and a normally inactive pawl actuated by the gate and 90 cooperating with the setting mechanism; including in combination a second trip in the path of the blanks and a second normally inactive pawl cooperating with the setting mechanism and actuated by the second trip 95 independently of the first named trip.

4. A grading machine of the kind having 100 detecting mechanism for measuring successive blanks according to thickness, grading mechanism, setting mechanism responsive to the detecting mechanism and controlling the grading mechanism, a normally open gate in advance of the detecting mechanism, a trip in 105 the path of the blanks for controlling the gate, said trip being independent of and in advance of the grading mechanism, and a normally inactive pawl actuated by the gate and 110 cooperating with the setting mechanism; including in combination a second trip in the path of the blanks in advance of the first named trip and a second normally inactive pawl actuated by the second trip, adapted to be operated by the blanks independently of the first named trip to render 115 the second pawl active before the first pawl is rendered active by the closing of the gate, and again to render the second pawl inactive before the first pawl is rendered inactive by the opening of the gate.

5. A grading machine of the kind having 120 detecting rolls for measuring successive blanks according to thickness and a normally inactive setting pawl; including, in combination, tripping mechanism comprising a rock shaft, a trip finger fixed to the rock shaft and extending close to the nip of the rolls, a gravity plunger to operate the pawl, a lever fulcrumed between the rock shaft and the gravity plunger and a cam on the rock shaft to actuate the lever.

6. A grading machine of the kind having detecting mechanism for measuring successive blanks according to thickness and grading mechanism responsive to the detecting mechanism, including means for propelling the blanks from the detecting mechanism to the grading mechanism comprising an endless belt having a friction surface adapted frictionally to engage the blanks throughout their whole length and an anti-friction presser shoe adapted to hold the blanks in frictional engagement with the belt.

7. A grading machine of the kind having detecting rolls for measuring successive blanks according to thickness and grading mechanism responsive to the detecting rolls, the lower roll having an annular groove at its middle, including means for propelling the blanks from the detecting rolls to the grading mechanism comprising an endless belt having a friction surface adapted frictionally to engage the blanks, the working stretch of said belt passing through the groove in the lower detecting roll, and an anti-friction presser shoe adapted to hold the blanks in frictional engagement with the belt.

8. A grading machine including feeding and detecting rolls, and means for guiding blanks to said rolls comprising a pair of guide members, each made in two sections, one of which is angularly adjustable with relation to the other.

9. A grading machine including feeding and detecting rolls, and means for guiding blanks to said rolls comprising a pair of guide members, each made in two sections, one of which is angularly adjustable with relation to the other, and means to adjust the two angularly adjustable sections simultaneously and in parallelism.

10. A grading machine including feeding and detecting rolls, and means for guiding blanks to said rolls comprising a pair of guide members, each having a main section and an angularly adjustable section hinged thereto, means to shift the two main sections together transversely of the machine, and stationary means on which the hinged sections are fulcrumed, adapted to swing the hinged sections angularly with relation to the main sections when the main sections are so shifted.

11. A grading machine including feeding and detecting rolls, and means for guiding blanks to said rolls comprising a pair of guide members, each having a main section and an angularly adjustable section hinged thereto, means to shift the two main sections together transversely of the machine, stationary abutments between the hinged sections to hold them in spaced relation, and a spring to hold said sections against the abutments, whereby the hinged sections will be swung

angularly with relation to the main section when the main sections are so shifted.

12. A grading machine including feeding and detecting rolls, and means for guiding blanks to said rolls comprising a pair of guide members, each having a main section and an angularly adjustable section hinged thereto, and means to adjust both the main sections and the angularly adjustable sections toward and from each other simultaneously and to like extent, to vary the width of the guideway without varying the angular relation of the sections.

13. A grading machine including feeding and detecting rolls, and means for guiding blanks to said rolls comprising a pair of guide members, each having a main section and an angularly adjustable section hinged thereto, a shaft having oppositely threaded parts adapted to adjust the main sections toward and from each other, members on which the angularly adjustable sections are fulcrumed, a shaft having oppositely threaded parts adapted to adjust said members, toward and from each other, and means connecting the two shafts for rotating one from the other to cause the main sections and the angularly adjustable sections to move toward and from each other simultaneously and to like extent.

14. A grading machine including feeding and detecting rolls, and means for guiding blanks to said rolls comprising a pair of guide members, each having a main section and an angularly adjustable section hinged thereto, a shaft having oppositely threaded parts adapted to adjust the main sections toward and from each other, abutment members between the angularly adjustable sections to hold them in spaced relation, a spring to hold said sections against the abutment members, a shaft having oppositely threaded parts adapted to adjust said abutment members toward and from each other, and means connecting the two shafts for rotating one from the other to cause the main sections and the angularly adjustable sections to move toward and from each other simultaneously and to like extent.
